MAGNETIC FIGURE TOY

John J. Leonard, Wyncote, Pa.

Application October 12, 1949, Serial No. 120,949

8 Claims. (Cl. 46—45)

1

This invention relates to figure toys, and particularly to animated toys in which figures or articles are caused to move in various patterns or paths.

Although it is recognized that there have been many attempts to cause figures to move about upon a surface by moving magnets in certain patterns thereunder, as previously provided these have been of limited use, and the patterns of figure movement have been restricted to a given relatively small area, and interchangeability of patterns, or movement of the figures out of the circumscribed path pattern and into another path pattern has been impossible.

It is among the objects of this invention: to provide moving figures with alternative paths of movement; to improve figure toys; to provide elaborate patterns of figure toy movements; to provide figure toys with controlled alternative patterns of movement so as to enhance the observer's interest therein; to provide mechanical improvements in toys controlled in movements by moving magnetic devices; and to provide other improvements as will appear as the description proceeds.

Fig. 1 represents a fragmentary side elevation of a form of the invention involving skiers, a ski-tow on a "mountain" and a passenger car and track device in which the figures representing skiers move on toy-train tracks to a loading and unloading platform, and after taking a ski-tow toward the top of the mountain move alternately on two paths down the imitation mountain, after which they may be shunted back into the toy car.

Figs. 2, 3, 4, and 5 represent fragmentary details of the form of the device shown in Fig. 1.

Fig. 6 represents a fragmentary plan, partially in section, of the delivery end of the railway car of Figs. 1 to 3.

In Figs. 1 to 6 inclusive, the invention is shown as applied to a ski-tow and ski-slope, and movable figures simulating skiers, having alternate down-hill paths for the skiing figures, and with the entire system arranged and disposed for lateral translation of the collection of skier figures in a toy railway train, both in approaching and leaving the simulated skiing terrain.

A pair of rails or tracks 50', of conventional toy train construction is provided, having a portion parallel to the edge 51 of a station platform 52. The platform extends generally horizontally in predetermined vertical spacing from the level of the tracks 50', and merges into the sloping surface 53 of the imitation mountain 54.

The surface of the mountain 54 provides two

paths for the skiers 59 to traverse in the downward descent thereof respectively the "slalom" path 69 and the "downhill" path 79, while affording a single path 89 up the mountain. The respective paths are outlined beneath and concealed by the superficial simulation mountain surface, representing snow or the like, and comprise channels or grooves for guiding magnetic units. These channels include a single groove 55 leading up the slope under path 89, leading into an upper transverse groove 56, leading into a junction 57 between a generally linear groove 58 beneath downhill path 79, and a sinuous groove 60, beneath slalom course or path 69, both 15 extending down the mountain 54. The downwardly inclined and extending grooves 58 and 60 merge at 61 in communication with a ski-tow approach, transverse groove 62, and the loading front platform groove 63. Grooves 62 and 63 20 merge at 64 into the upwardly sloped groove 55. At the junction 57 an automatically operated switching element 70 is mounted. The purpose of switching element 70 is to separate the guided magnets alternately into those following channel 25 60 and those following channel 58, so as to separate the skiers following a sinuous course down the mountain, as in an imitation of slalom, from those following a straight downhill course. A manually operated switch element 71 is disposed 30 in the junction 61, shown in a transitory mid-position in Fig. 3, operable between limited positions in which either all skiers move toward the front 51 of the platform 52, for loading into the car to be described, or all skiers move in a transverse movement in line with the groove 62 to climb the slope on the upward path aligned and registering with the ski-tow to be described.

To actuate the magnetic devices moving in the grooves, a motor 73, through gears 74 and 75, 40 drives a double pulley 76 mounted on the journaled shaft 77, so that the pulleys lie generally parallel to and beneath the superficial surface upon which the skiers slide. The pulley 76 is disposed toward the lower portion of the slope, 45 more or less adjacent to the groove 62. Toward the upper part of the mountain a pulley 80 is mounted on the journaled shaft 81 in general parallelism with pulley 76. An endless belt 82 extends about pulley 80, and one of the pulleys 50 of the double pulley 76, and carries a plurality of rigidly mounted telescopic members 83. Members 83 comprise a plurality of telescopic elements containing suitable springs internally as to bias the telescopic elements into their shortest axial length. At their free ends the members 83 carry

the groove-riding permanent magnet plows 84. The plows are preferably rounded at the ends so as to follow curves in the guides formed by the grooves. When the telescopic members 83 have retracted to their shortest extent they all ride in series alignment in one direction with belt 82 in the single vertical groove 55, and they are also guided in series alignment through upper groove 56. Depending upon the attitude of the automatic switch member 70, the approaching plows move automatically alternately into groove 58 and groove 60. It will be apparent for this purpose that the switch 70 might be manually controlled to steer all of the skiing figures successively down a single path, or selectively down either or both paths. Regardless of the path followed, with switch 71 moved to the left, all of the plows will be guided successively into series progression through the horizontal groove 62 and return into groove 55. With switch 71 to the right, all of the plows in progression move through front groove 63 beside tracks 59.

The toy car 90 having wheels 91 guidable on the tracks 59' is provided with the usual controls and motors so as to be controllably movable and stoppable on said tracks. A miniature electric motor 92 is mounted internally of the car and has a shafting extending longitudinally of the car, as indicated at 93, with suitable pulleys and belting to drive the shafts of the rollers to be described. An endless conveyor belt 94 extends longitudinally horizontally of the car, mounted on and stretched between the permanently mounted rollers 95 and 96 at the ends of the car. Roller 95, illustratively, is driven by a belt drive 97 on pulley 98 of the roller 95, from a shafting pulley on the shaft 93. Roller 96 is similarly driven. An entrance door 100, is pivoted on a vertical hinge 101 at one end of the car, and toward the lower end thereof carries a rigid shaft 102 normal to the door 100. At the free end shaft 102 carries the rigid guiding abutment 103 extending outwardly generally parallel to the door 100 and arranged to overlie the upper surface of the platform 52 adjacent to its edge 51, when the car is juxtaposed thereto and the door is opened. Journalled for rotation on the shaft 102 is the roller 104. At the side of the car opposite to the door is the fixed driven roller 105, driven by belt 106 and pulley 107 on roller 105. Belt 106 passes about a pulley 108 on shaft 93. A conveyor belt 110 passes about the car-mounted roller 105 and the door mounted roller 104, overlying the upper run of the longitudinal conveyor belt 94, and stretched taut when the door is opened to its proper full extent, as indicated in Fig. 4. As the door closes, the guard 103 and the roller 104 clear the side of the car at the door opening and the belt 110 becomes limp and untensioned and may collapse without disassociation from its rollers. However, this is not of particular moment because at this time it has no functioning as a conveyor. When the door opens the conveyor is again stretched tight for conveyor functions. In order to control the door, a solenoid-operated spring-biased link 111 is pivoted to the door toward the upper end thereof at 112, and the opposite end of the link is slideable in the solenoid spring housing 113, pivoted at 114 to the bracket 115 mounted on the inner end of the car. An exit door 116 is provided at the other end of the car, which is similar to door 100. An exit conveyor belt 117 is journalled on the door 116 and extends transversely of the longitudinal belt 94, of such length and dispo-

sition when tensioned with full opening of the door, as to lie over platform 52, extending across edge 51 thereof, terminating substantially adjacent to the groove 63. In order to assist movements of the ski figures between transverse belt conveyors 118 and 117, and longitudinal conveyor 94, a vertical longitudinally extending transversely curved guide is provided, comprising the entrance guiding portion 118 overlying conveyors 110 and 94, the longitudinally extending portion 120 adjacent to conveyor 94, and the exit guiding portion 121 overlying conveyors 94 and 117. The guiding portions 118 and 121 at the car side are generally parallel to the transverse conveyor belts to which they are juxtaposed, and curve about and across said transverse conveyor belts to force the skiing figures 59 from one transverse belt upon the longitudinal belt and from the latter to the other transverse conveyor.

As an aid in the simulation of the skiing resort, a form of ski-tow may be provided aligned on the upward course thereof with the path 89, so that figures progressing up the face of the slope externally of the surface 53 by the magnetic attraction of the respective plows 84, move with the tow. The illusion is created by a series of inverted U-shaped poles 125 asymmetrically straddling the concealed groove 55 and path 89, the lowermost of which poles 125 at one side journals a shaft 126 generally vertical, extending downwardly into the foundation of the mountain 54, and at the lower end carrying a pulley 127, connected by a driving belt 128 with the lower pulley of the double pulley 16. The upper exposed end of the shaft 126 carries a pulley or drum 130, which through short belt 131 drives the pulley 132 on shaft 133, parallel to shaft 126, carrying the lower drum or pulley 134. The top pole 125 of the series journals a shaft 135 on which a drum 136 is mounted. An endless belt 140 passes about the drums or pulleys 134 and 136, preferably guided by and internally of the poles 125, each reach of which, at spaced intervals, carries a dangling pivoted angle piece 137, in simulation of one or another form of conventional ski-tow. If desired, a mere cable may be used. So long as the motor 73 runs, therefore, the rope of the ski-tow turns about the axes of the pulleys 134 and 136 and the figures of the skiers pass up the hill between the legs of the straddling poles 125.

In operation, let it be assumed that a series of independent skiers 59 is provided, in a plurality thereof, which may all be identical or may be of various forms to simulate various types of skiing. Let it be assumed, to start, that the figures are all crammed into the car, mounted on the longitudinal belt, and stopped at the rear of the car by the convergence of the guide 121 and the closed exit door 116. This is the loading disposition of the figures as they will normally be mounted in the car at the conclusion of the activities of the figures on the ski slope, as will be explained. Of course, at this time, the ski slope is empty.

The car moves about the various tracks of the toy train system and finally when desired by the operator, by suitable switching, moves onto the track 59', coming to a stop alongside of the platform contiguous to edge 51 thereof. At this or any other desired point, the motor 73 of the ski-tow and moving control devices starts. What is observed at this time is the ski-tow simulation moving about its two end axes. Everything else that moves is concealed. However, the plow mag-

nets will be traversing the respective grooves. By manipulation of proper electric switches (not shown) the rear or exit door of the car is then opened to its fullest extent overhanging the platform, bringing the exit conveyor belt 117 into tautened extended position in its rollers, terminating substantially over or in line with the front groove 63 of the platform 52 so that as any figure 59 drops from the delivery end of belt 117, it drops to the station platform within the magnetic attraction of the next plow passing along groove 63. The rear or exit conveyor belt 117 preferably extends under the longitudinal belts 94, and the series of skiers in the car are mounted on belt 94 abutting the curved guide 121, and held in mutually abutting relation by the closed door and the elements mounted thereon and extending into the car. As soon as the door 116 is opened the end ski figure 59, of the series of stored figures, moves from the longitudinal belt 94, is deposited on the now tightened and running transverse belt 117, and moves across the edge 51 of the platform 52 to deposit on the upper surface of the platform, within the effective field of the next plow-shaped magnet that passes in guided relation through groove 63. The deposited skier 59 is drawn by such plow across the platform surface and into the entrance to the ski-tow, thence up the hill, across and down the hill again, either on the sinuous or the linear path depending upon the setting of the switch 70. Each succeeding skier emerges from the car and is deposited on platform 52, upon which it is then moved in translation. During this egress of the skiers, the switch 71 continues to be set to guide all of the plow magnets 84 into the front groove 63. As soon as the last skier is on the platform, the switch 71 is thrown and the magnetically drawn figures move from the bottom of the ski slope across the surface above transverse groove or slot 62, to the ski-tow. As soon as the last skier is out of the car, the electric control may be actuated to close the door 116. While usually the drives to conveyor belts are stopped at this time, by stopping the motor 92, this is not necessary, as the closing of the door releases the tension on the exit conveyor belt 117, and the driven roller for same is permitted free rotation relative to the released or tension relieved belt 117, so that no untoward results attach to the continuation of the drive.

After the series of skiers have completed their endless rounds of ski activities, according to the desire of the operator, it will be assumed that it is desired to load them all in the car. For this purpose, with continuance of the drive from the motor 92 in the car, with the longitudinal belt 94 running, with the rear door 116 closed, and with the drive roller 105 for the entrance conveyor belt 110 rotating against a relaxed and untaut belt 110, the front, or entrance door 100 is automatically opened by the closing of the proper switch means. The belt 110 on its roller 104 is swung with the door 100 to substantially horizontal alignment with the upper surface of the platform 52, at the edge 51 thereof, with the guiding element 103 overhanging the platform and the skier path over groove 63. The belt 110 immediately starts running, with the upper surface moving into the car 90. The switch 71 is then swung so that all plows approaching the merging area 61 from either the linear path 58 or the sinuous path 60, are guided into the path or groove 63. As each plow magnet successively moves from the merging area 61 into 75

the forward groove 63, the ski figure magnetically attached to it is forced by the guide 103 from its path of movement with the plow, transversely thereto, to drop onto the end of the entrance conveyor belt 110. Moving inwardly in this belt, it impinges against the curved portion 118, of the stationary guide, to disposition on and movement with the belt 94. Each skier moves on belt 94 toward the opposite (exit) end of the car, where, remaining vertical, they pile up horizontally on the belt 94, with the belt moving beneath the retarded figures, until all of the skiers are in the car. At this point the door 100 is closed by its solenoid or spring action, thus releasing the tension on the entrance belt 110, the motor 92 is then stopped, leaving the ski figures mounted in upright position on the belt 94, in position to be moved outwardly from the car through rear exit door 116. The car can then be driven on rails 50, by suitable switch manipulations, as with cars of this type in toy trains. Any additional mechanisms to maintain the toy figures upright and for guiding them in and out of the car that may be desired or necessary will be provided.

The interest with which a toy of this sort is operated and observed will be understood.

Having thus described my invention, I claim:

1. In toys, a generally continuous surface including a slope out of the horizontal, a plurality of magnetic units, means for moving said magnetic units sequentially in series generally parallel to said surface on the lower side thereof, means establishing a plurality of paths in closed circuits for the respective magnets in their sequential series, means for predetermining a path of said plurality of paths for a given magnet of said plurality, a plurality of figures of magnetically attractable material respectively to follow the respective magnets in their respective paths by movement in translation on the upper side of said surface, and auxiliary path means operable for causing a magnet to move out of the said closed circuits and to move a figure on said auxiliary path.

2. In toys, a generally continuous surface depicting a snow scene including a slope out of the horizontal, a plurality of magnetic units movable under and relative to said surface, means establishing a plurality of mutually intersecting paths of movement of said magnetic units, means at the intersection of said paths for selecting the path to be traversed by a given magnetic unit as an automatic function of the path determination of the preceding magnetic unit, means for moving said magnetic units sequentially in series along said paths, a plurality of figures symbolic of skiers, the lowermost elements of which comprise ski-simulations and containing magnetically attractable material mounted on said surface to follow respective magnetic units by movement in translation on said surface.

3. In toys, a generally continuous surface simulating a ski slope including a portion inclined out of the horizontal, a plurality of figures of magnetically attractable material mounted on said surface for motion thereon in simulation of skiing activities, a plurality of magnets, means delineating two paths for motion of said magnets under said surface traversing said inclined surface portion, said paths having mutual intersection with a common single path traversing said inclined surface portion, means for sequentially moving said magnets on the respective paths, means at

the intersection for switching the magnets successively from the common path to one or the other of the plurality of paths whereby figures attracted to the respective magnets move in translation in a common path on said surface in one direction thereon and follow alternate paths of motion on said surface in another direction thereon.

4. In toys, a surface simulating a ski slope, a plurality of figures of magnetically attractive material mounted on said surface for motion thereon in simulation of skiing activities, a plurality of magnets, means delineating two paths for motion of said magnets under said surface, said paths having mutual intersection with a common single path, means for sequentially moving said magnets on the respective paths, means at the intersection for switching the magnets successively from the common path to one or the other of the plurality of paths whereby figures attracted to the respective magnets move in translation in a common path on said surface in one direction thereon and follow alternate paths of motion on said surface in another direction thereon, a toy train track, a toy car movable on said track, means for guiding and moving the said figures from said surface into said car, and means for guiding and moving said figures from said car to said surface.

5. In toys, a surface simulating a ski slope adjacent to the platform of a toy train track, a car movable on said track, a longitudinal conveyor belt mounted for movement longitudinally of said car, a movable door for said car, means for moving said door open and closed, a transverse conveyor belt, a roller journalled for rotation on said door and arranged when the door is open to operatively tighten said transverse belt to extend into operative relation to said platform, magnetic means beneath said surface for moving skiing figures in translation on said surface and on said platform adjacent to said transverse conveyor belt, and means for moving said respective conveyor belts to successively move said figures from said surface into said car, and said means for moving said door operative for closing said door to permit translational movement of said car on said tracks.

6. In toys, a surface simulating a ski slope adjacent to the platform of a toy train track, a car movable on said track, a longitudinal conveyor belt mounted for movement longitudinally of said car, movable door for said car, means for moving said door open and closed, a transverse conveyor belt, a roller journalled for rotation on said door and arranged when the door is open to operatively tighten said transverse belt to extend into operative relation to said platform, magnetic means beneath said surface for moving skiing figures in translation on said surface and on said platform adjacent to said transverse conveyor belt, means for moving said respective conveyor belts to successively move said figures from said car onto said surface, and said means for moving said door operative for closing said door to permit translational movement of said car on said tracks.

7. In toys, a substantially continuous surface including a slope out of the horizontal, a series of magnets, means for moving said series in se-

quence adjacent to but beneath said surface in a closed cycle of movement, a series of figures each representing human beings having snow-engaging element simulations on the lower extremities in contact with said surface, respectively response to the magnetic attraction of given associated magnets and arranged to move in translation across said surface in moving with said respective magnets, means establishing a common single path of travel for part of said closed cycle traversing said slope and for establishing two paths of travel reversely traversing said slope for the respective magnets of said series in another part of said cycle, and means for automatically switching one magnet from the common path to one of the two said paths in response to the passage of an immediately preceding magnet from the common path to the other of said two paths, so as to cause alternate attracted figures to follow the said two paths while all of said figures follow the single path in making a complete cycle.

8. In toys, a generally continuous surface including a portion inclined out of the horizontal and representing a ski slope, a plurality of figures of magnetically attractive material disposable on said surface for movement relative thereto, a guide groove under the surface forming a common path traversing said inclined portion, a plurality of guide grooves forming plural paths intersecting each other and the common groove at the beginning and ending of the common groove and traversing said inclined portion, said grooves all having substantially uniform spacing from adjacent areas of said surface, switch means adjacent such intersecting of the grooves, an endless conveyor generally parallel with said surface, a plurality of telescopic arms mounted for movement with the conveyor, magnets on the ends of the respective arms disposed for guided movement in said grooves, said switch means including automatic resetting means operative by the passage of one magnet into and along one of said plural paths to cause a successive magnet moving along and from the common path to move into and along another of said plural paths, whereby said respective figures are caused to traverse said surface in accordance with selected combinations of said paths.
